UNITED STATES PATENT OFFICE.

FREDERICK HUNTINGTON CLARK, OF NEW YORK, N. Y., AND MORRIS M. WHITAKER,
OF NYACK, NEW YORK.

SHIP.

1,334,349.

Specification of Letters Patent. Patented Mar. 23, 1920.

Application filed August 5, 1918. Serial No. 248,474.

To all whom it may concern:

Be it known that we, FREDERICK HUNTINGTON CLARK, of borough of Manhattan, city, county, and State of New York, and MORRIS M. WHITAKER, of Nyack, county of Rockland, State of New York, have invented certain new and useful Improvements in Ships; and we do hereby declare the following to be a full, clear, and exact description of the same, reference being had to the accompanying drawings, forming a part of this specification, and to the reference-numbers marked thereon.

Our present invention has for its object to provide means for the economical transportation of lumber by water, and broadly considered it embodies the idea of transporting "dimensioned lumber", preferably squared timbers of commercial sizes, built into the form of a ship's hull and capable of navigation on the high seas. Our invention has for its further object the construction of a raft having exteriorly the lines, or hull formation, of a vessel, and which interiorly may be built either solid or partly solid by the piling or stacking of the timbers. Another feature of our invention relates to the manner in which the timbers are laid, both transversely and longitudinally, to provide the necessary strength in the completed hull to withstand the buffeting of the seas, and prevent the displacement of both the exterior timbers and the interior timbers comprising the cargo, by the pitching motion of the ship, collision, gunfire or torpedo attack. To these and other ends the invention consists in certain improvements and combinations of parts, all as will be hereinafter more fully described, the novel features being pointed out in the claims at the end of the specification.

In the drawings:

Figure 1 is a side elevation of a ship built in accordance with our invention illustrating certain general features;

Fig. 2 is a half-breadth plan, or top view, of one longitudinal half of the ship;

Fig. 3 is a horizontal sectional view taken on a plane just below the deck;

Fig. 4 is a body plan being a transverse sectional view taken substantially on a midship plane;

Fig. 5 is an enlarged cross-sectional view showing the manner of laying up the tim-

bers to form parts of the bow and stern when the sides of the hull are drawn inward:

Fig. 6 is another detail view illustrating perspectively one way in which the lumber may be cut and handled to form the bow and stern portions;

Fig. 7 is an enlarged detail illustrating the tie rod fastenings;

Fig. 8 is a detail view of one of the tie rod saddles;

Fig. 9 is a detail view showing the dowels used for securing the timbers against relative movement.

Fig. 10 is a detail view, showing the manner of filling the spaces between adjacent tie-rods by means of planks.

The transportation of lumber, as such, is confronted with many difficulties because of its weight and bulk and this is especially so in carrying it "over seas", as only a comparatively small quantity can be loaded into the hold of the average freight carrying vessel. Then too, the construction of such vessels imposes undesirable limitations in the length, sizes and cross-sectional sizes of the timber carried, and further, the storing, or loading of the latter in the hold of a vessel makes it impracticable to ship in this manner any but seasoned, or kiln dried lumber, thus often delaying its delivery unduly, even when the demand for it is most urgent.

In carrying out our invention we preferably use "green sticks," i. e., the lumber just as it comes from the saw mill, and in practice ships embodying our invention are built at the nearest launching-point to the mill to which the logs are delivered from the forest. The lumber is cut to given sizes, rectangular, and as large in cross-sectional area as possible, thus obviating the loss incident to recutting and permitting the delivery at foreign ports of timbers which may be resawed as desired at any time after they are received. In constructing a ship's hull in accordance with our invention we lay down central longitudinal timbers to form the keel and keelson and extending laterally therefrom lay other timber, side by side, to form the bottom which is preferably rounded, as shown. The triangular, or sector shaped spaces, lying below the knee point of the hull, where the sides rise from the bottom, commonly termed the bilge, are filled solid, and over this filling a flooring is laid

of timbers extending transversely of the keel and of the full width of the hull at any given transverse section, their length varying fore and aft of the widest midship point.

- 5 A series of closely standing timbers are placed on the ends of the floor pieces and comprise vertical extending interior ribs outside of which, on the extreme ends of the floor pieces, are stacked the side, or wall timbers. The space formed within the vertical pieces may be used for the cargo timbers, and in the arrangement of these we also contribute to the stability of the craft, by arranging some of these to form central and intermediate longitudinally extending bulkheads. Over the top of the hull thus formed deck timbers are placed, the length of these being slightly greater than the width of the hull, and resting upon the side walls and the intermediate bulkheads. The various members described may be laid in place without the use of forms other than suitable launching ways for supporting the keel and bottom timbers. The timbers, after being thus laid up, are secured by suitable binding devices such as surrounding tie rods, chains, or cables, which act as hoops, some of which extend from the ends of the deck timbers around the hull, while others may extend between the gunwales, either beneath, or between, the deck timbers, and coöperate with the latter to bind the side walls of the hull together.

35 Various methods may be employed for combining the pieces of material, and in the drawings we have shown the preferred form for securing the necessary strength in the entire body of timbers to withstand the strains and stresses arising in a floating body when encountering heavy sea waves and prevent the mass from pulling apart, or breaking up, by the strains caused during the sagging and hogging moments.

40 The ship is not built in the ordinary way; but by laying up, or piling, the timbers in successive layers according to a predetermined design, having for its fundamental idea stability, strength and speed, all proportional to its displacement, and while 45 these objects may be accomplished in various ways, our preferred method of construction is that set forth in the following detail description.

45 In the body plan view Fig. 4, which is an athwart-ship section, the dotted lines illustrate the cradle timbers, part of which may ultimately be used as the launching ways. On these is first laid the false keel 1, surmounted by the keelson 2. The latter is 50 composed of a number of longitudinally extending beams, three in the present instance, being shown and indicated by *a*, *b* and *c*, to the lowermost of which the false keel 1, composed of a number of long timbers, is 55 surely fastened by bolts, or lag screws 1^a,

The meeting ends of these timbers are scarfed, and the keelson timbers are also rigidly secured together against endwise movement by "gaining" them on their top and bottom edges; *i. e.*, cutting out of their opposite faces depressions for one quarter of their length at each side of the transverse center, thus leaving the timber full size at each end for one-fourth of its length. Sticks thus cut may be placed butt to butt in horizontal alinement, and in each succeeding vertical row the joints will break with those in the adjacent upper and lower rows, and their large full size end portions will interlock in the smaller, or reduced, middle sections of the adjacent sticks. This gaining is shown in detail in Fig. 7 and it will be understood that the relative proportion of the full sized and cut away portions of the timbers may be varied as desired. In lieu of this method of securing the sticks against longitudinal movement upon one another they may be locked by dowels, or keys, indicated by 1^b in Fig. 9. The latter means of interlocking the sticks is found preferable in certain instances where the desirability, or necessity of fastening cannot easily be determined until after the stacking has been done, in such places the grooves for the dowels may be drilled, or chiseled by suitable automatic tools and the dowels driven into place.

55 The bottom timbers are for the most part square and are laid side by side, those forming the garboard strakes being indicated by 3, and those comprising the bottom planks proper by 4. If desired the entire bottom may be flat and laid with the rise shown, but we prefer to make the angle at 5, about as shown, between the two parts of the bottom not only for the purpose of more nearly simulating a curve, but for the more important reason of adding to the clamping action of the surrounding tie members when these are applied and placed under tension. 60 The garboard strakes adjacent the keel are cut to the necessary angle, as shown at 2^a, and similar pieces are provided at the knee 5 and beyond the outermost bottom plank, as indicated by 4^a.

65 The bilge is filled solid at each side of the keelson by timbers 6, which, for the most part, are rectangular, except a few at the outer edges of the bottom, levels the lower faces of which are cut on angles determined by the shape of the bottom as a whole. This shaping of the timbers does not result in a material loss of the wood, as many of the smaller triangular filling pieces are merely the sides, or corners, cut from the larger pieces, and most of such smaller pieces are capable of being later resolved into boards.

70 The floor pieces 7 are heavy timbers such as 12" x 12", or 18" x 18", of a length substantially equal to the full width of the ship 75

and their ends projecting beyond the bottom planks. They extend transversely over the keelson and the bilge filling and are laid side by side forming a longitudinal layer extending throughout the greater portion of the hull, their length varying as the lines of the hull are drawn inwardly toward the bow. The space beneath the overhanging ends of the floor pieces 7 and the outermost bottom planks 4^a is provided to accommodate the fore and aft filling pieces 8, which are rounded as shown, and also project laterally somewhat beyond the floor pieces. The curved surfaces of the filling pieces obviate a sharp bend in the tie rods, and by projecting them beyond the ends of the floor pieces they will always be forced laterally toward the keel and cause the timbers comprising the bottom planks and garboard strakes to be held under compression.

The sides of the hull are built up of rectangular timbers, which form a main, or outer, wall, and are interlocked as by "gaining" in the manner before described. A desired curve in the wales is obtained by selecting timbers of different width and locating the widest ones in the center of the tier. As an indication of appropriate sizes of sticks that may be used, and the manner we lay them up, we have indicated in Fig. 4 the side wall as composed of twelve pieces each 12" in height. The lowermost piece 9 may be 8" wide, the next one 10 may be 10" wide; each of the next two pieces 11 may be 12" in width; and the three central pieces 12 may be 14" wide. The four upper rows of timbers 13, covered by the rail, or gunwale strip, 14 may each diminish correspondingly in width. Within the side walls are the vertical rib pieces 15, which are stacked on end in close order, fore and aft amidships, as far as the lines of the hull permit. The rib pieces are slightly shorter than the side walls to provide longitudinal scruppers 15^a and extending longitudinally over the top of all of said ribs are filling pieces, or compression strips, 16 which prevent the pieces 15 from working upwardly.

At the center of the hull we provide preferably two longitudinal bulkheads spaced apart sufficiently to provide space for the stepping of the masts, and the accommodation of such ballast as may be deemed necessary. These center line bulkheads are composed of the vertical rows of timbers indicated by 17 and 18, which are "gained" or otherwise interlocked, or secured, against independent longitudinal movement, it being understood that in piling the timbers joints between abutting pieces are broken, or staggered. The bulkheads rest upon the floor pieces 7, and in the space between them railroad rails 19, as shown in dotted lines, or other heavy objects, may be placed; or the space may be filled by a few large timbers as

indicated by 20, and above the latter the space between the masts may be filled with short pieces of timber indicated by 21. The top edges of the bulkheads are about on a line with the tips of the rib pieces 15 to provide scruppers 22, which are open at the bow and stern and at the inner edges of these water passages filling blocks 23 are located, which maintain a downward compression on the bulkhead piles of timber.

The deck beams 23 are of large dimensions, like the floor pieces 7, but their ends project beyond the gunwales and instead of laying them side by side they are preferably spaced apart, the spacing varying according to the size of the timber; for instance, if these timbers are of a size 18" x 18" they may be separated a distance of three feet. Each of the deck beams carries a number of the encircling tie rods, which are attached to its opposite ends and by separating these beams it is possible to use another set of tie rods, or binders, which occupy the space between the beams, and in themselves are sufficient to hold the mass together during a voyage. Another object in thus arranging the parts resides in the fact that in the transverse spaces of the deck we provide compression tie rods which serve to draw the gunwales inwardly, and these rods we employ to hold the saddle blocks which carry the second set of binders in place.

The cargo space lying between the verticals, or ribs 15 and the center bulkheads is filled with dimensioned lumber, preferably in large sizes, and one or more tiers thereof, as indicated by 23^a will be staggered to prevent one layer from attempting to slip over another. The cargo lumber in whatever manner it is stacked will be of such sizes as to completely fill the hold space so that it is compressed horizontally, to support the bulkheads, ribs and side walls, and vertically by the downward pressure of the deck beams.

Surmounting the deck, along the sides thereof, bulwarks 23^b may be formed by piles of lumber preferably composed of timbers of equal size assembled so as to have the form in cross-section, of a right angle triangle, the upwardly extending leg of the triangle comprising the outer face of the pile which lies within the plane of the side wall of the hull. This lumber may be so arranged on the fore and aft portions of the ship as to give sheer to the form of the structure, and also to act as a protection to the living quarters of the crew. The bulwarks are preferably secured in place by lashings 24 engaging inner and outer eye bolts 25 and 26 which pass through the deck beams and may be secured to the latter before these are permanently fixed in the position which they are to occupy in the completed structure.

The living quarters of the crew are entirely above the deck, as indicated by 31, and comprise water tight compartments which may be built in any suitable manner, and are secured in place by lashings 31^a. Ingress and egress to and from these compartments is obtained through roof hatches 31^b.

The shape of the hull is designed, in so far as practicable, to permit the use of long, rectangular timbers, and at the same time provide it with such lines as render it both seaworthy, and capable of being propelled by its own power. One of the most important features of our invention resides in the provision of means by the use of dimensioned timber whereby the desired shape of the bow and stern lines may be provided. The sticks, or larger pieces of timber, from which the forward portion of the hull of the vessel is built up, are selected of a commercial, transverse-sectional size, such as a timber 12"x12", and with these we use other timbers which are multiples of such dimensions, such smaller pieces being used as filling strips in the corners, or angles, at the outside of the hull, formed between a lower timber, and the upper one, which projects laterally thereof, as shown in Fig. 5. It will be understood, of course, that in every instance the largest size of timber will be employed which will fit in a given space, and still conform to the general desired curvature; that is, if the angular space provided by the lateral projection of one full size timber beyond another will accommodate a smaller timber of say a size of 3"x6" such size will be employed rather than to use two pieces of 3"x3" placed one on top of the other. The carrying out of this idea is illustrated in Fig. 5, which is a fragmentary cross-sectional view of a hull showing the arrangement of the timbers as they may appear at any one of several points where the narrowing in of the buttock and bow lines occurs. Another illustration of the stacking of multiple size pieces is shown in Fig. 6, which depicts in a single view how, by the use of timbers of different sizes and lengths, the inward curving of the bows, both longitudinally and vertically, is effected.

The timbers being finally assembled in their desired positions throughout the entire hull of the vessel are secured together by means of the two sets of tie rods before mentioned, the one set 27 being those which have their threaded ends passed through holes bored in the overhanging ends of the deck beams, where they are secured by the nuts 27^a. The other set of tie rods, indicated by 28, have their threaded ends passed through perforated bosses 28^a on the saddle pieces 29, and engage with nuts 28^b. The rods 27 and 28 may be made in one or more

pieces, according to the size of the hull, and their ends are threaded for a sufficient distance to permit them to be placed under considerable tension, in the first instance, and also to allow them to be tightened as occasion may require. The saddle pieces 29 are held in position against the gunwale timbers by the deck tie rods 30, the threaded ends of which are received in the perforated bosses 30^a, on the outside of which are the nuts 30^b. The last mentioned tie rods may extend horizontally, but we prefer to arch them slightly in the center so that the strain imparted to them will impart a compressional force against the filled blocks 16 and 22^a.

The rough exterior of the hull of a vessel built in accordance with the present disclosures, is smoothed over to reduce the skin friction as the body is propelled through the water. This part of the work may be made to give the finished appearance desired, but for practical purposes, and because of the fact that it is not the intention to attempt to drive the mass at anything but a moderate speed, it is unnecessary to do more than to fill the spaces between adjacent tie rods. Throughout the greater portion of the ship these spaces may be filled by planks 32, of thickness equal to the diameter of the tie rods, extending endwise vertically between the latter, and spiked to the side wall timbers. In some places short lengths of these spacing pieces will be utilized. If desired, an outer skin, or surface, may be formed by boards, or planks, overlying the rods and the filling pieces 32, and which will be nailed or spiked through the latter. However, as no attempt is made to maintain the craft in a water tight condition, the skin planking may be quickly put in place and arranged in such a way that such lumber will, upon delivery, have substantially its original value at the saw mill and contribute to the value of the whole mass. To this end, some of the sheathing planks will extend horizontally, as indicated by 33, while others may be arranged diagonally, as indicated at 34, the latter being used wherever this disposition of the planks enables them to be more easily molded to the lines of the hull.

The craft may be propelled by any suitable source of power, preferably by the use of sailing equipment, and in the present illustrations we have shown a schooner rig to which might be added as an auxiliary equipment, a hydrocarbon engine with the usual propeller located beneath the stern, as indicated in dotted lines, the shaft of which will be driven by bevel gears from a counter shaft similarly geared to the driving shaft of the engine (not shown) inclosed in a suitable deck house.

A ship constructed in accordance with our invention affords means for the transportation on long voyages of a great quantity of

lumber in the form most desired at the point of delivery, namely in large timbers. Further, in the practice of our invention another advantage will be found in that we provide for using lumber which in the green state is improved by subjecting it to the action of sea water which acts to cure the lumber by driving out the sap.

We claim as our invention:

1. A ship's hull composed of a plurality of timbers first cut to commercial dimensional sizes, then laid in rows to form a substantially solid body having the desired exterior lines of the hull, the butts of adjacent timbers in one row breaking joints with those of adjacent rows, means for securing the timbers of some of said rows against longitudinal movement relative to the rows of timber at their opposite sides and means for binding the mass of timbers together as a whole.

2. In the construction of a ship's hull, the combination with a plurality of longitudinal timbers of given sizes laid to form the bottom, other timbers similarly laid and fitted to fill the bilge, floor pieces arranged transversely of the latter and extending substantially the width of the hull, and other longitudinal timbers resting on the floor pieces and stacked substantially in solid formation the outer timbers forming the sides of the ship, and means for securing the mass together.

3. A ship's hull comprised of timbers laid longitudinally to form the keel and bottom and fill the bilge, floor pieces extending transversely of the former, other longitudinally extending timbers forming the side walls and cargo, deck pieces arranged transversely of the hull and means extending from the ends of the deck pieces beneath the bottom and acting to secure the mass of timbers together.

4. A ship's hull formed by laying courses of longitudinally extending timbers to form the bottom and keel and fill the bilge, floor timbers extending transversely over the latter, other courses of longitudinal timbers resting on the floor pieces, those courses on the exterior comprising the side walls being interlocked against relative longitudinal movement, deck beams arranged with their ends projecting beyond the side walls and tie rods carried by the ends of said beams and extending beneath the bottom of the ship.

5. A ship's hull formed of dimensionally cut timbers extending side by side in longitudinal rows and laid to form the bottom and sides of the hull, some of the rows of timbers being secured to adjacent rows to prevent relative longitudinal movement, a course of timbers extending transversely of the hull, other interior courses of cut timbers comprising the cargo substantially filling

the body of the ship, and stacked in endwise and sidewise relationship to prevent their shifting and means encircling the ship for binding the mass together.

6. A ship's hull formed of dimensionally cut timbers extending side by side in longitudinal rows and laid to form the bottom and sides of the hull, some of the rows of timbers being secured to adjacent rows to prevent relative longitudinal movement, a course of timbers extending transversely of the hull and supporting the side wall rows, other interior rows of cut timber disposed above and below the transverse timbers and substantially filling the space between the bottom and side walls, deck beams extending over the latter and resting on the inclosed timbers and means extending around the sides and bottom and securing the deck beams, and sides and bottom pieces in compressional engagement with each other and with the inclosed timbers.

7. A ship's hull formed of dimensionally cut timbers laid in longitudinal rows side by side to form the bottom and side walls of the hull, and other similar pieces of lumber comprising inner horizontal layers and vertical rows substantially filling the interior of the hull, some of the rows of both the interior and exterior timbers being secured to adjacent rows to prevent their relative longitudinal movement, other rows of the interior timbers being disposed to prevent lateral shifting of the mass and members extending around the hull and binding the entire mass of timbers together.

8. A ship's hull formed of dimensionally cut timbers laid in longitudinal rows side by side to form the bottom and side walls of the hull, and other similar pieces of lumber comprising inner horizontal layers and vertical rows substantially filling the interior of the hull, deck beams overlying the interior and side wall timbers and arranged in spaced relation, one set of securing means extending from the ends of said beams around the bottom of the hull and a second set of securing devices including saddles at the junction of the deck and side walls and extending completely around the hull in the spaces between the deck beams.

9. A ship's hull formed of dimensionally cut timbers laid in longitudinal rows side by side to form the bottom and side walls of the hull, and other similar pieces of lumber comprising inner horizontal layers and vertical rows substantially filling the interior of the hull, some of the rows of both the interior and exterior timbers being secured to adjacent rows to prevent their relative longitudinal movement, other rows of the interior timbers being disposed to prevent lateral shifting of the mass, deck beams extending transversely across the top of the hull and engaging the top interior

and exterior timbers, said beams being spaced one from another, a set of compression members extending from the ends of said timbers beneath the hull, and a second set of compression members encircling the hull in the intervals between the deck beams.

10. A ship's hull having a bottom formed of dimensionally cut timbers laid to form the keelson, other timbers placed side by side to form the garboard strakes adjacent the keelson and similar timbers beyond forming the bottom planks, the planks extending upwardly and outwardly at an angle to the strakes, side wall timbers stacked vertically and composed of pieces progressively wider from the top and bottom of the walls to their middle point forming the wales, means supporting the side walls independently of the bottom, cargo 20 timbers substantially filling the hull, tension members extending beneath the bottom of the hull and upwardly at the sides thereof.

11. A ship's hull having a bottom formed of dimensionally cut timbers laid to form 25 the keelson, other timbers placed side by side to form the bottom of the hull extending upwardly and outwardly at each side of the keelson, floor pieces resting upon the keelson and projecting beyond the bottom 30 timbers, compression blocks beneath the floor pieces engaging the outermost bottom timbers and projecting beyond the floor pieces, side wall timbers stacked vertically on the ends of the latter with their outer 35 faces projecting beyond said floor pieces and tension members extending beneath the bottom timbers around the compression blocks and upwardly along the side walls.

12. A ship's hull having a bottom formed 40 of dimensionally cut timbers laid longitudinally with an upward rise at each side of the longitudinal center, other timbers laid longitudinally and cut to fill the bilge space and transversely extending floor timbers covering the latter, and projecting at 45 their ends beyond the outermost bottom timbers, of side wall timbers resting upon and projecting beyond the ends of the floor timbers, compression blocks resting against 50 the outermost bottom timbers and also projecting beyond the extremities of the floor timbers and tie rods extending beneath the bottom and upwardly in engagement with the compression blocks and side wall 55 timbers.

13. A ship's hull formed of dimensionally

cut timbers laid longitudinally to form a substantially solid body and give the lines of a ship to the bottom and sides, transverse timbers extending over the tops of the 60 mass and spaced one from another, a set of tie rods extending around the mass and secured to the ends of the transverse timbers and a second set of tie rods connected to saddles at the junction of the deck and side walls disposed in the spaces between said timbers and surrounding the mass.

14. A ship's hull formed of a mass of dressed timbers stacked in substantially solid formation and arranged to approximate the lines of a ship, tie rods overlying the exterior rows of timber and binding the mass together, filling pieces between said rods and sheathing extending over said pieces and rods.

15. A ship's hull formed of dressed timbers comprising a layer forming the exterior bottom, vertical courses comprising the sides, and two spaced longitudinally extending central bulkhead courses, the adjacent timbers of said side and bulkhead courses being interlocked against relative lengthwise movement, deck timbers extending transversely over the tops of said courses, the rods securing the deck timbers and side 80 and bottom timbers together and masts stepped between the bulkheads.

16. A ship's hull formed of dressed timbers comprising a layer forming the exterior bottom and a central keelson, floor 90 timbers laid transversely upon the keelson and extending substantially the full width of the hull, vertical courses of timbers stacked on the ends of the floor pieces, and two spaced longitudinally extending bulkhead courses centrally disposed on the floor pieces, deck timbers overlying the side and bulkhead courses, and tie rods extending from the ends of the deck timbers around the hull.

17. A ship's hull formed of dimensionally cut timbers laid longitudinally to form a substantially solid body and give the lines of a ship to the bottom and sides, saddles at the junction of the deck and sides, a set of tie-rods connected to said saddles and extending around the mass to bind the same together, and sheathing extending over said saddles and rods.
